FLUID SPREADER

Solomon Goldspiel and Joseph Meisler,
Brooklyn, N. Y.

Application July 30, 1946, Serial No. 687,162

1 Claim. (Cl. 91—30)

1

This invention relates to devices for use in spreading or distributing fluids on surfaces of any type and kind. More particularly, the invention deals with a device comprising a can-like casing with means on the casing adjustably controlling discharge of the fluid therefrom and for spreading fluid evenly over a surface and, further, with means for moving the device over a surface. Still more particularly, the invention deals with a device of the character described, wherein a single control regulates a plurality of independent discharges for providing a substantially even distribution of fluid throughout the entire length of the casing of the device to facilitate even spreading and coverage of the fluid on a surface.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a side and sectional view through the casing of a device made according to our invention, with parts of the construction broken away.

Fig. 2 is a section on the line 2—2 of Fig. 1.

Fig. 3 is a section on the line 3—3 of Fig. 1, omitting part of the background structure; and

Fig. 4 is an enlarged sectional view on the line 4—4 of Fig. 1.

The device is in the form of a can-like casing 10, substantially oblong and rectangular in form and comprising side walls 11 and 12 and end walls 13 and 14, the side walls 11 and 12 joining in a top wall 15. The bottom of the casing 10 is closed by an inwardly set and substantially thick bottom plate 16, which leaves the lower ends of the side wall 11 and 12 protruding, as seen at 11' and 12' in Figs. 2 and 3 of the drawing. The end walls 13 and 14 also extend downwardly, as seen at 13', 14', Fig. 1, and generally conform to the contour of a supplemental bottom wall 17 arranged in wide spaced relationship to the bottom wall 16 to form a fluid distributing chamber 18 therebetween.

The bottom wall 17 has raised side walls 19, which curve outwardly and downwardly to form longitudinal channels 20, note Fig. 4. The downwardly extending wall parts 21, defining one side of the channel, terminate in upwardly extending flanges 22 spaced with respect to the walls 20 to form narrow channels 23, in which the lower ends 11', 12' of the walls 11 and 12 are adapted to extend. At spaced intervals along the wall extensions 11', 12' are cutouts forming yield-

able latch tongues 24 and, at adjacent portions of the flange 22 are other cutouts forming latch tongues 25, preferably wider than the tongues 24 to insure alignment and engagement with the tongues 24, 25 one with respect to the other. The tongues 24 are directed upwardly and the tongues 25, downwardly. It will, thus, be seen that, in attaching the bottom wall 17, the ends 11', 12' extend downwardly into the channels 23 and the yielding tongues spring one over the other and snap into holding position. Detachment is possible by simply springing the flanges outwardly, as will be apparent. Only one pair of the latch tongues 24, 25 is shown in detail in Fig. 4 and indicated in Fig. 1, but three of these will be arranged along each flange 22, one centrally and one at each end portion of the flange.

Extending upwardly from the supplemental bottom wall 17 are two stop pins 26, 26' to check downward movement of a valve head or bar 27, as later described. The supplemental bottom wall 17 has a series of longitudinal discharge passages 28 centrally and longitudinally thereof through which fluid in the chamber 18 is discharged onto a surface, over which the device is moved.

The end wall 13 has an outwardly projecting threaded admission tube 29 closed by a suitable cap 30 facilitating filling of the chamber 31 of the can or casing. The top wall 15 has a nut body 32 welded or otherwise secured thereto, in connection with which is threaded a valve stem 33 having at its upper or outer end a milled head 34, by means of which the stem 33 may be rotated.

A suitable packing gland 35 may be employed around the valve stem within the nut body. Also secured to the top of the can is an indicating finger 36 which may register with suitable markings on the top of the head 34 to indicate adjustments of the bar 27 in control of the discharge of fluid from the chamber 31 through a series of discharge passages 37 spaced centrally and longitudinally of the bottom wall 16. The passages 37 are relatively small and open into larger passages 38 forming valve seats 39 between said large and small diameter passages 37 and 38.

Loosely supported in suitable sockets 40, in the bar 27, are a plurality of valves 41 adapted to operate upon the seats 39 in sealing the discharge 37. The valves 41 carry at their upper ends reduced needles 42 which extend through the passages and are, at all times, in the passages 37. The needles 42 are slightly conical in form so as to control, to some degree, the discharge 37 through the respective passages.

It is also preferred that the outermost valves on the bar 27 are slightly longer than the next adjacent valves and the latter slightly longer than the innermost valves. In other words, considering the left side of Fig. 1, the valve 41a is slightly longer than valve 41b and 41b is slightly longer than 41c. The same is true of the three valves at the other end portion of the bar 27. In this way, positive sealing of all valves is insured in moving the bar 27 upwardly. The end valves, as at 41a, seat first; the valves 41b seat second and the valves 41c, seat last, the bar 27 springing sufficiently in accomplishing this result. The difference in length will be slight and is indicated in the drawing.

The free mounting of the valves 41, in the bar 27, also insures proper seating of all valves.

The lower end of the valve stem 33 is reduced, as seen at 43, where it passes through the bar 27 and a washer 44 is mounted on the reduced end 43 and held in place by a cotter-pin 45, so as to permit free rotation of the valve stem in the bar 27 in the operation of raising and lowering said bar. The bar is retained against swinging movement by the square ends, one of which is shown at 46, engaging the end walls 13' and 14', as will be apparent. The bottom 16 has a valve stem guide sleeve 47 welded or otherwise secured thereto to guide and reinforce the stem 33 in its passage through said wall. It is also preferred that a packing gland 48 be arranged between the sleeve and the wall 16, as shown.

The upper end of the valve stem has an elongated vent passage 49 which extends into the chamber 31 and the valves 41 are in open position so as to insure discharge of the fluid from the chamber 31. However, when the valves are raised into closed position, the vent will be sealed, thus facilitating any desired handling or packing of the complete device.

On the side walls 13 and 14 are pivot pins 50, 50', in connection with which the side members 51, 51' of a handle member yoke 52 are adapted to be pivoted. The side members 51, 51' have, on their inner surfaces, inwardly extending recessed bases 53, 53' adapted to be sprung into engagement with either one of two short, rounded pins 54, 54', 55, 55' in retaining the yoke 52 in different positions of inclination, as is indicated in Fig. 2 of the drawing, in moving the fluid spreader device over a floor or other surface. In Fig. 2, the yoke 52 is shown in engagement with the pins 54, 54'. However, in getting under articles of furniture or the like, the yoke may be swung downwardly for engagement with the pins 55, 55', as will be apparent. Secured centrally to the cross-head 56 of the yoke 52 is a suitable handle member, indicated in dot and dash lines at 57, in Fig. 2 of the drawing.

It will be noted from a consideration of Fig. 1 of the drawing that the discharge apertures 28 are preferably arranged directly beneath the valves 41. It will be understood, however, that the fluid discharged into the chamber 18 will be distributed and the back and forth reciprocation of the device over the floor will also serve to distribute the fluid in the chamber 18 for discharge through the several passages 28 to accomplish a relatively even spreading of the fluid on the surface by spreaders or applicators 58, 58'. The spreaders or applicators are in the form of blade-like units detachable with respect to the channels 20 and each comprise a spring-plate 59 and a wiper-strip 60 of greater width than the plate 59 so as to protrude below the lower end

of the plate and said lower end of the strip is preferably slit at longitudinal intervals, as seen at 61, in Fig. 1 of the drawing. The strip 60 may be composed of any suitable semi-firm, but flexible, material, such as a felt strip and, by slitting the strip, as at 61, a substantially smooth wiping effect can be accomplished over surfaces which may be slightly irregular, the slits 61 forming independently flexing members 62 therebetween. 10 The blade unit also includes a U-shaped mounting strip 63 which firmly joins the upper end portions of the plate 59 and strip 60 and forms a means for mounting and retaining the blade unit in the channel 20, while permitting 15 forcible detachment from the channel in cleaning, repair or replacement of the blade units as and when desired. It will be understood, however, that the blade mountings in the channels 20 is sufficiently secure to prevent accidental displacement in frictional engagement of the strip 60 with the surface over which the device is moved. The two strips 60 form below the bottom wall 17 a space into which the fluid is discharged to facilitate spreading of the fluid by 20 the wipers or applicators 60. The wiper or applicator strips are backed-up and reinforced by the spring strips 59 which maintain the spacing referred to. It will also be understood that sole support of the device is taken up by the strips 60 25 in conjunction with the strips 59, the strips 60, however, maintaining sole contact with the surface and being sufficiently rigid to accomplish this result. It will, of course, be apparent that strips of different structures can be employed in 30 different uses of the device and in the application of different types and kinds of the fluid.

One use of the device is for the application of liquid waxes to floors or other surfaces and, particularly, waxes of this type and kind which 40 simply require even spreading over the surface. There are other types and kinds of fluids which are regarded as coating fluids used for coating floors for protection of the surfaces, particularly in coating linoleum and various other types of composition flooring, generally referred to as floor tiling. It will be understood, however, that the device may be made in different sizes for different uses. It is contemplated, however, that one use would comprise a casing or container of 45 a gallon capacity thereby making it possible, by reason of the simple and economic construction of the complete unit, to sell the unit as a complete assemblage in the purchase of a gallon of the fluid. The container part of the device can 50 then be turned in in the purchase of a replacement, allowance being made for the can or casing in the second purchase and the seller or distributor can care for cleaning and servicing of the can for the re-sale. On the other hand, the 55 complete applicator can be sold in the purchase of a number of cans of fluid and the purchaser can, from time to time, re-place the wiper blade units and have, at all times, a simple, practical and economic form of device for spreading or applying fluids of any type or kind to surfaces of any kind.

It will be understood that the side members 51, 51' of the handle yoke can be quickly and easily sprung-off from the pins 50, 50' in packaging, 60 shipment and/or storage of the device. In Fig. 1, the valve bar 27 is shown in its lowermost position of adjustment. It will be understood, however, that any adjustment can be provided from the wide open to a fully closed position in rotation of the milled head 34. The thread 33' on

the valve stem 33 will be preferably of a quick-thread type so as to accomplish fully open to fully closed position within one complete revolution of the valve stem, thereby facilitating control through the gauge or indicating finger 36.

The showing in Fig. 1 of the drawing of the different heights in the valves 41a, 41b and 41c is exaggerated. In actual practice, the difference in valve lengths will be slight, but sufficient to accomplish the independent seating of the valves as heretofore stated.

Having fully described our invention, what we claim as new and desire to secure by Letters Patent is:

A device of the class described comprising a 15 casing having an inset fixed bottom wall leaving depending walls on the casing, means for introducing fluid into the casing, a detachable supplemental bottom wall forming in the casing below the fixed wall a distributor chamber, means on 20 the supplemental bottom wall forming upwardly and downwardly extending channels, depending walls of the casing fitting in said upwardly extending channels, yieldable means on said depending walls and channel forming means for retaining the supplemental bottom wall against displacement from the casing, the fixed bottom wall having a plurality of longitudinally spaced discharge apertures, a plurality of needle valves controlling said apertures, a single manually 25 operated member adjustably supporting said valves in regulating the flow of fluid from the casing into said distributor chamber, said supple-

mental bottom wall having longitudinally spaced discharges, through which fluid is adapted to pass onto a surface, wipers detachably mounted in said downwardly directed channels and extending below the lower surface of the supplemental bottom wall for spreading fluid discharged onto a surface, said needle valves being greater in length at the ends of the member than at the central portion thereof to provide independent seating of said valves, whereby end apertures of the fixed bottom wall are closed prior to the central apertures, and a handle member pivotally supported on the casing for moving the device over a surface.
